DESIGN FOR A BEACH ENSEMBLE SUIT

Margaret Ann Waters, New York, N. Y.

Application May 5, 1941, Serial No. 100,781

Term of patent 3½ years

To all whom it may concern:

Be it known that I, Margaret Ann Waters, a citizen of the United States, residing at 149-39 Roosevelt Avenue, Borough of Queens, city of New York, in the county of Queens and State of New York, have invented a new, original, and ornamental Design for a Beach Ensemble Suit, of which the following is a specification, reference being had to the accompanying drawing forming a part thereof, and in which:

Fig. 1 is a front view of a beach ensemble suit showing my new design,

Fig. 2 is a rear view of the beach ensemble suit shown in Fig. 1, and

Fig. 3 is a plan view of the trouser-like portion of the beach ensemble suit shown in Fig. 1.

I claim:

The ornamental design for a beach ensemble suit, substantially as shown.

MARGARET ANN WATERS.
